UNITED STATES PATENT OFFICE.

ALBERT E. PAGE, OF BROOKLYN, NEW YORK, ASSIGNOR TO SCOTT & WILLIAMS, INCORPORATED, OF NEW YORK, N. Y., A CORPORATION OF MASSACHUSETTS.

STRIPING ATTACHMENT FOR KNITTING MACHINES.

Application filed April 18, 1928. Serial No. 270,985.

This invention relates to circular knitting machines and an attachment for making vertical stripes in the fabric by means of knitting in a plating yarn where the stripes are desired. One object of my invention is to produce an attachment which is simple and accurate. In the accompanying drawings I have shown my mechanism embodied in one of the well-known Scott & Williams type of revolving needle cylinder seamless hosiery machines.

In the drawings:

Fig. 1 is a front elevation of the head of a knitting machine, partly in section, showing my invention embodied therein;

Fig. 2 is an elevation of the head of the same machine taken from the right side;

Fig. 3 is an exaggerated plan view of the bobbin stand and needle cylinder taken on the line 3—3 of Fig. 2;

Fig. 4 is a detail of part of the bobbin stand driving gear from the plane indicated by the line 6—6 in Fig. 1;

Fig. 5 is an exaggerated diagrammatic plan view of the bobbin stand and needle cylinder showing interengagement of the yarns; and

Fig. 6 is a similar view showing the relation of the bobbin stand to the needle cylinder a moment later than in Fig. 5.

In fabric made by my attachment supplementary yarns of the desired color or colors are wrapped around the needles which are to knit the stripe or stripes and these striping yarns are knit in with the ordinary yarn, the striping yarns being knit on the outside of the fabric so that the stripe will show. These yarns are fed from a bobbin stand having an axis permanently fixed on a center eccentric to the center of the needle cylinder, this bobbin stand carrying the yarns, take-ups, and yarn fingers.

Referring now to the drawings, the machine has the usual bed-plate B, revolving needle cylinder 260, latch ring 550, pivoted on the bracket 401 carried by the bed-plate, and a main pattern drum 120 for the purpose, among other things, of actuating a thrust rod 460 to control the feeding of the splicing yarns. Projecting upwardly from the latch ring 550 is a bracket 11 carrying the bobbin stand and gears for driving same. This bobbin stand comprises an axis or spindle 12 set a fraction of an inch off center with relation to the needle cylinder 260, this

axis being keyed to a large horizontal bevel gear 13 revolvably carried in the bracket 11. This bevel gear 13 meshes with a bevel pinion 14 driven by bevel gear 15 and pinion 16, the latter being mounted on a vertical shaft 17 driven from the main shaft in any usual manner, such for instance as that shown in the Patent 1,282,958 issued to Robert W. Scott on October 29, 1918.

On the axis 12 above the bracket are mounted the spools 18 carrying the yarn Y, and the take-up devices 19. After leaving the take-up devices the yarns pass through guide holes 20 in the bevel gear 13 and thence directly to yarn fingers 21 hinged on a bracket 22 carried by the ring 23, the ring being fast on the axis 12 below the bracket 11. These fingers are normally held in a vertical position by springs 24 and when in this position are retracted with relation to the needles N in the cylinder 260, lying a short distance within the needle circle at the point where the circle of yarn fingers approach nearest to the needle cylinder.

These yarn fingers are adapted to have their toes 25 tipped radially outward by an adjustable cam 26 engaging the upper end of the yarn fingers. This cam 26 is pivotally mounted to the bracket 11 by means of a yoke 27 which permits it to be swung down into operative relation with the upper end of the yarn fingers, as desired. This cam is normally held in operative relation with the upper ends of the yarn fingers by means of a spring 28 fastened to one end of the yoke 27 and to the bracket 11, the exact operative level of the cam being adjustable by means of a screw 29 in the yoke (Fig. 1). The yoke is lifted and lowered by one end of a lever 30 pivoted on the latch ring 550 and having at its other end an eccentrically adjustable pin 31 overlying the upper end of a thrust rod 460. This thrust rod, as usual, is raised and lowered by means of a high cam 501 and a low cam 502 on the main pattern drum 120, the pattern drum thereby serving to determine when the yarn fingers shall be tipped out into operative relation with the needles. This lever 30 has a spring 32 attached thereto which tends to tip the lever upwardly against the yoke and hold it in its uppermost position. It will therefore be observed that when the thrust rod is lowered the springs 28 and 32 will raise the cam 26 out of contact with the yarn fingers 21 and that when the thrust

rod is raised the cam 26 will be lowered against the tension of the two springs. By means of having two heights of cams on the main pattern drum 120, as already mentioned, 5 and cutting the upper ends of the yarn fingers in the two manners shown in Fig. 1, it is possible to selectively control the yarn fingers. Thus it is possible to produce a striped instep with a plain sole.

10 As can be noted from the dot and dash lines in Fig. 5 the yarn fingers in effect drop behind and then get ahead of their corresponding striping needles every revolution of the cylinder, but that the axis 12 is permanently fixed eccentrically to the center of the needle cylinder, the distance equal to the two dot and dash lines seen near the bottom of Fig. 1. The axis thus is within the needle circle, by which is meant that, whether or not 15 it extends below the top of the needle cylinder, it lies inside of the cylindrical space defined by the circle in which the needles normally turn. The path of the yarn fingers intersects and is eccentric to the needle circle in the same sense whether it is above or 20 below the top of the needle cylinder.

It will be obvious from the description already given that since the toes of the yarn fingers are revolved on a radius which is 30 shorter than that of the needle cylinder their circumferential speed is less than that of the needles and that when the toe has been projected across the needle circle it will drop back relatively to the needles and when 35 turned toward the center of the needle circle will have wrapped the yarns around some of the needles. In Figs. 3, 5 and 6 the needles upon which the yarn has been or is to be wrapped are shown in outline while the remainder of the needles are shown solid.

40 For the purposes of illustration I will now describe the operation of the attachment when making a striped stocking. When making the welt of the stocking where no vertical stripes are desired the thrust rod 460 will be riding on the surface of the pattern drum 120 and the springs 28 and 32 will therefore be holding the cam 26 up above the upper ends of the yarn fingers 21. It will 45 be noted that the axis 12 is revolved in unison with the needle cylinder at all times by means of the gears and pinions 13, 14, 15 and 16, and that the axis carries with it the spools of 50 yarn Y, the take-ups 19 and the yarn fingers 21.

55 When it is desired to begin making vertical stripes around the complete circumference of the stocking the revolution of the pattern drum 120 causes the thrust rod to ride up on 60 the high cam 501 which lowers the yarn finger cam 26 into the path of the upper ends of all the yarn fingers 21 as shown in Fig. 1. This cam 26 being semi-circular engages the upper ends of the yarn fingers a short distance less than 180° in advance of the knock-

ing-over point (indicated by an arrow in Figs. 3, 5 and 6), and pushes the toes of the yarn fingers radially outward over the needles and holds them there until shortly before the needles reach the knitting cams. 70 The striping needles can be raised above the adjacent needles by means of cylinder jacks in any well-known manner, as for instance by the mechanisms shown in the patents to Smith 1,169,436, Bosworth 1,402,394 or Scott 75 1,628,517. Each yarn finger is adjusted to cross the circle of needles in a manner which lays that striping yarn Y just ahead of the corresponding striping needles, the yarn coming from the inside of the needle circle. 80 The needles then pass ahead of the yarn finger and the latter as it crosses back inside the needle circle completes the wrapping of the thread around the needles. It will be noted that each striping yarn is held at the inside of the striping needle at the sinker after the stripe is once commenced, thus insuring accurate wrapping of the yarn around the needle. The distance between the needles around which the yarn has been laid and the 85 yarn finger increases to the maximum at a point opposite the yarn finger cam 26, the extra amount of striping yarn thus drawn being retrieved by the take-up devices 19, one for each yarn. It will be observed that the 90 yarn fingers are revolving with a lesser linear velocity than the needles, on an axis which is fixed eccentrically to the center of the needle circle which insures accurate timing of the 95 yarn fingers relatively to the needles.

100 When the leg of the stocking is finished and the machine starts making the heel, the thrust rod 460 drops off the high cam 501, thus allowing the yarn finger cam 26 to rise out of contact with the upper ends of the 105 yarn fingers 21 and stop the striping. When the heel has been completed, the thrust rod rides up on to the low cam 502 lowering the 110 yarn finger cam slightly till in engagement with the yarn fingers whose upper ends are not cut away. The fingers acted on can have their upper ends shaped similarly to the ones shown on the right in Fig. 1. Yarn fingers shaped in this manner are located on the portion of the circle of needles which is knitting 115 the instep and in this way a striped instep and plain sole are obtained.

120 In each striped course the striping yarn fingers are moved round and round and successively out and back in order to cause their feeding ends to cross the needle circle twice in each revolution, the said ends moving in a path which lies mainly within the needle circle but intersects it since the movement along this path is about an axis having a fixed eccentricity with respect to the center of the needle circle. In addition, the movability of these fingers permits the fingers to be rendered ineffective for feeding to the needles at a selected point in the machine's cycle as 125 130

- determined by the pattern drum since, when the latter operates the mechanism to cause the cam 26 to lift, the fingers move to and remain in a position in which they do not feed.
- 5 The same results may be effected by other arrangements embodying underlying thoughts of this invention, namely, the rotation of the feeding points on an axis of fixed eccentricity and in a path intersecting but 10 lying mainly within the needle circle, and the movement to an inoperative position at a predetermined point in the cycle of the machine. Heretofore there has been no union of the advantages of the eccentric arrangement, which causes the yarn fingers to approach and recede from the needle bank while moving at lower linear velocity than the needles, with the advantages of rendering the yarn fingers ineffective after a desired 15 number of striped courses, except by varying the eccentricity to give the latter.
- It will be obvious that by means of my attachment a simple and accurate means of producing vertical stripes in fabric has been produced and one which is adapted to be attached to the modern revolving needle cylinder machine for the production of striped fabric having striped insteps and plain soles.
- 20 I claim:
- 30 1. A circular knitting machine having a revolving needle cylinder, a revolving bobbin stand, yarn fingers to receive yarn therefrom and a support for said yarn fingers, the axis of said support being mounted within the needle circle with fixed eccentricity with respect to the center of the needle cylinder and the yarn fingers thereon revolving with lesser linear velocity than the needles, said yarn fingers being adapted to be moved into and 35 out of operative relation with the needles.
2. A circular knitting machine having a revolving needle cylinder, a revolving bobbin stand, a yarn finger support and pivoted yarn fingers on said support revolving with lesser 40 linear velocity than the needles, in combination with means adapted to move said yarn fingers into and out of operative relation with the needles by tipping the yarn fingers relatively to the said support, the axis of said 45 bobbin stand being fixed in its eccentricity relatively to the needle cylinder and being within the needle circle.
3. A circular knitting machine having a revolving needle cylinder, a revolving bobbin 50 stand, yarn fingers receiving yarn therefrom and a revolving support for said yarn fingers, the axis of said support being mounted within the needle circle with fixed eccentricity with respect to the center of the needle cylinder and the yarn fingers thereon revolving with lesser linear velocity than the needles, said needle cylinder and said support having the same angular velocity, said yarn fingers being adapted to be moved into and out of 55 operative relation with the needles.
4. A circular knitting machine having a revolving needle cylinder, a revolving bobbin stand, yarn fingers to receive yarn therefrom and a revolving support for said fingers, the axis of said support being mounted within the needle circle with fixed eccentricity with respect to the center of the needle cylinder and the yarn fingers thereon revolving with lesser linear velocity than the needles, said needle cylinder and said support having the same angular velocity, said yarn fingers being adapted to be moved into and out of operative relation with the needles. 70
5. A circular knitting machine having a revolving needle cylinder, a yarn finger supporting means revolvably mounted with its axis within the needle circle and having a fixed eccentricity with respect to the center of the needle cylinder, and a yarn finger, at an off-center point on said supporting means, adapted to be moved into and out of operative relation to the needles and to revolve at a linear velocity different from that of the needles. 80
6. A circular knitting machine having a revolving needle cylinder, a yarn finger supporting means revolvably mounted with its axis within the needle circle and having a fixed eccentricity with respect to the center of the needle cylinder, and yarn fingers supported thereby adapted to be moved into and 85 out of operative relation to the needles and to revolve at a linear velocity lower than that of the needles. 90
7. A circular knitting machine having a revolving needle cylinder and a yarn finger, means for revolving the feeding end of said yarn finger in unison with the needles in a path intersecting and having a fixed eccentricity with respect to the needle circle and at a linear velocity lower than that of the needles, together with means for moving said yarn finger into and out of operative relation 100 to the needles. 105
8. A circular knitting machine having a revolving needle cylinder, revolving bobbins, yarn fingers to receive yarn from said bobbins and means for revolving the feeding ends of said yarn fingers in a path intersecting and having a fixed eccentricity with respect to the needle circle and at a linear velocity lower than that of the needles, together with means for moving said 110 yarn fingers into and out of operative relation to the needles. 115
9. A circular knitting machine having a revolving needle cylinder, revolving bobbins, yarn fingers to receive yarn from said bobbins and means for revolving the feeding ends of said yarn fingers in unison with the needles in a path intersecting and having a fixed eccentricity with respect to the needle circle and at a linear velocity lower than that of the needles, together with means for moving said 120 yarn fingers into and out of operative relation to the needles. 125
10. A circular knitting machine having a revolving needle cylinder, revolving bobbins, yarn fingers to receive yarn from said bobbins and means for revolving the feeding ends of said yarn fingers in unison with the needles in a path intersecting and having a fixed eccentricity with respect to the needle circle and at a linear velocity lower than that of the needles, together with means for moving said 130 yarn fingers into and out of operative relation to the needles. 130

10. A circular knitting machine having a revolving needle cylinder and striping yarn fingers, means for rotating said fingers in unison with the needles but at a lower linear velocity upon an axis having a fixed eccentricity with respect to the center of the needle circle and in such a way that the path of the feeding ends of the said fingers intersects the needle circle, together with pattern controlled means for rendering said fingers ineffective for feeding to the needles at a predetermined point in the cycle of operations of the machine. 11. A circular knitting machine having a revolving needle cylinder, a spindle having a fixed eccentricity with respect to the center of the needle cylinder, striping yarn fingers supported by said spindle and turning there-with and means for moving said fingers turn for turn with the needles and in such a way that the path of their feeding ends intersects the needle circle. 12. A circular knitting machine having a revolving needle cylinder, striping yarn fingers mounted to turn about an axis having a fixed eccentricity with respect to the center of the needle circle, and means for moving said fingers turn for turn with the needles and in such a way that the path of their feeding ends intersects the needle circle.
- In testimony whereof I have signed my name to this specification.

ALBERT E. PAGE.
